UNITED STATES PATENT OFFICE.

WILLIAM G. NAISMITH, OF DENVER, COLORADO, ASSIGNOR TO THE DENVER ROCK DRILL MFG. CO., OF DENVER, COLORADO.

FLUID-OPERATED MOTOR.

Application filed December 6, 1922. Serial No. 605,290.

The present invention relates to distributing valve mechanism for motors of the type operated by compressed air or other expandable motive fluid, and the object is to provide valve mechanism that will secure high speed of the piston with a heavy blow and a minimum amount of recoil. The present embodiment of the invention hereinafter disclosed has been found to secure these desirable results and make it unnecessary to add surplus weight to the machine or require the operator to bear heavily against it to keep it in proper action.

In the accompanying drawings:—

15 Figure 1 is a plan view of a form of construction that is at present considered preferable.

20 Figure 2 is an end view of the same with parts shown in section,

25 Figure 3 is a longitudinal sectional view illustrating the position of the valve when the piston has made its operative stroke, and is initiating its return movement,

30 Figure 4 is a longitudinal sectional view, with the parts reversed from Figure 3,

Figure 5 is a view in elevation of the valve,

35 Figure 6 is a longitudinal sectional view through one of the valve chest closure plugs.

40 Figure 7 is a detail longitudinal sectional view through the cylinder and with the piston removed in order to show the exhaust permitting passageway opening into the central portion of the piston chamber.

45 In the embodiment disclosed a cylinder member is employed embodying a barrel 7, a rear end wall 8 and a front head 9, forming a piston chamber 10. In this piston chamber is mounted a piston 11 which may be of any desired or well known type.

50 On one side of the barrel 7 is a valve chest 12 having a longitudinal bore 13 therethrough that forms a valve chamber. In the end portions of said valve chest and surrounding the chamber are eccentrically disposed annular grooves 14 that have communication with the end portions of the piston chamber through passageways 15. A motive fluid supply chamber 16 formed in one side of the valve chest has divergent passageways 17 leading to concentrically arranged annular grooves 18 surrounding the valve chamber adjacent to but spaced from the grooves 14. The supply chamber 16 is in communication with nipples 19 and 20 pro-

jecting at right angles from the valve chest and forming means that will permit the coupling thereto of motive fluid supply hose. Obviously when the hose is connected to one of these nipples the other is closed by a 60 suitable plug.

The valve chest is furthermore provided with an exhaust port 21 arranged on the opposite side to the chamber 16, and intersecting said port 21 is an exhaust permitting 65 passageway 22 that opens into the central portion of the piston chamber 10. The outer end of this passageway 22 is preferably closed by a plug 23 so that the exhaust through the passageway 22 will find an outlet through the port 21. The port 21 is also in communication with a central groove 24 surrounding the valve chamber and said groove 24 is in communication with the central portion of the piston chamber 10 by a 70 port 25. On opposite sides of the groove 24 are relatively deep grooves 26 that are in communication with the exhaust-permitting passageways 27 opening into the end 75 portions of the piston chamber 10, but between the passageways 15. Other annular grooves 28 are formed in the valve chest around the valve chamber between the grooves 18 and the grooves 26, and each of these grooves 28 is in communication with 80 the more distant groove 26 by a passageway shown diagrammatically at 29.

The open ends of the valve chamber are closed by plugs 30 secured in place by a central bolt 31 extending longitudinally 90 through the valve chamber, and these plugs have sleeve portions 32 that fit within the end portions of the valve chamber and terminate at the grooves 28. They are provided with radial openings 33 establishing communication between the grooves 14 and the interior end portions 34 of the bores of said sleeves, and said bores are enlarged at their inner ends, forming internal shoulders 35. The enlarged portions of the bores are in 100 communication with the grooves 18 through radial ports 36.

A reciprocating valve 37 operates in the valve chamber and surrounds the bolt 31. It is provided with a central groove 38, on 105 opposite sides of which are formed enlarged valve heads or flanges 39 that control communication between the grooves 26 and the exhaust groove 24. It is also provided with reduced end valve portions 40 adapted to 110

operate in the enlarged portions of the bores of the closure plug sleeves and by abutting against the shoulders 35, control communication between the grooves 14 and 18.

- 5 The operation of this valve is as follows: Assuming the parts in the position illustrated in Figure 3 and with motive fluid supplied to the chamber 16, the piston 11 has completed its working stroke and the 10 distributing valve 37 is in its rearmost position. It will thus be evident that fluid from the chamber 16 will pass through the left hand passageway 17 to the groove 18 and passing through the ports 36 will flow 15 into the outer end of the left hand closure plug 30, thence through the ports 33 into the groove 14, and by the passageway 15, will enter the left hand end of the piston chamber 10 and operate on the front end 20 of the piston to drive it rearwardly. The exhaust can take place through the passageway 22, port 25 and port 27 and out of the common exhaust port 21. As the piston travels rearwardly or to the right hand the 25 passageway 27 will be uncovered and consequently live motive fluid entering said passageway will find its way through the left hand groove 26 and the passageway 29 communicating therewith into the right hand groove 28. It will be noted by reference to 30 Figure 3 that the valve is so constructed that when its end is abutted against the internal shoulder 35 the outer face of the right hand head 39 of said valve will be in the groove 28 and this motive fluid will thus 35 act against said face. This face, however, is of slightly less area than the end surface of the valve exposed to the motive fluid flowing through the ports 36 and consequently the valve will not be overbalanced, but will remain in the position illustrated 40 in Figure 3 until the piston 11 has passed the rear passageway 27 when fluid then trapped behind the piston will be compressed 45 and the pressure thus built up will extend through the passageway 15, groove 14, ports 33 and the inner end of the bore 34. It will consequently be exerted against the right hand end of the valve and the combined 50 pressure thereby exerted on said end and on the face of the right hand head 39 will shift the valve to the right. The piston will now be in the position illustrated in Figure 4 and as shown motive fluid will 55 now enter through the groove 18, ports 36, bore 34, ports 33, groove 14 and right hand passageway 15 with the rear end of the piston while the exhaust will take place 60 through the reverse series of ports to that above described.

From the foregoing it is thought that the construction, operation and many advantages of the herein described invention will be apparent to those skilled in the art without further description, and it will be under-

stood that various changes in the size, shape, proportion and minor details of construction, may be resorted to without departing from the spirit or sacrificing any of the advantages of the invention.

Having thus fully described my invention, what I claim as new, and desire to secure by Letters Patent, is:—

1. In a fluid operated motor, the combination with a cylinder member having a piston chamber and a reciprocatory piston operating therein, of a valve chest having a valve chamber, means for supplying motive fluid to the end portions of the valve chest, intake passages for directing such motive fluid from the ends of the valve chest to the ends of the piston chamber, said piston chamber having exhaust permitting passages between the intake passages opening into the valve chamber between the supply means, an exhaust outlet from the valve chest between the exhaust permitting passages, a distributing valve in the valve chamber having end portions that control the passage of motive fluid from the supply means to the intake passages and spaced valve flanges that control the exhaust of fluid through the exhaust permitting passages to the outlet, the surface areas of the said end portions being greater than the surface areas of said flanges, means for intermittently supplying live motive fluid alternately against said smaller surface areas of the flanges during a portion of the piston stroke while maintaining corresponding pressure against the opposite larger surface areas to hold the valve against shifting, while relieving the corresponding end portion area of the valve of pressure, and means controlled by the piston as it reaches the limit of its stroke to deliver motive fluid under pressure against said end portions and supplementing the pressure against the flanges to shift the valve.

2. In a fluid operated motor, the combination with a cylinder member having a piston chamber and a reciprocatory piston operating therein, of a valve chest having a valve chamber, means for supplying motive fluid to the end portions of the valve chest, intake passages for directing such motive fluid from the ends of the valve chest to the ends of the piston chamber, said piston chamber having exhaust permitting passages between the intake passages opening into the valve chamber between the supply means, an exhaust outlet from the valve chest between the exhaust permitting passages, a distributing valve in the valve chamber having end portions that control the passage of motive fluid from the supply means to the intake passages, and an enlarged portion on an intermediate part of the valve for controlling the exhaust of fluid from the exhaust permitting passages to the outlet, said enlarged portion

having opposite pressure faces, and recesses around the valve chamber in which the faces operate, each of said recesses having a passageway communicating with the opposite exhaust permitting passage, and said passageways being out of communication with each other.

3. In a fluid operated motor, the combination with a cylinder member having a piston chamber and a reciprocatory piston operating therein, of a valve chest having a valve chamber, means for supplying motive fluid to the end portions of the valve chest, intake passages for directing such motive fluid from the ends of the valve chest to the ends of the piston chamber, said piston chamber having exhaust permitting passages between the intake passages, spaced grooves around the valve chamber into which the exhaust permitting passages respectively open, an exhaust outlet from the valve chamber between the grooves, a distributing valve in the valve chamber having reduced end portions controlling the passage of motive fluid from the supply means to the intake passages and having an intermediate portion provided with oppositely disposed pressure faces, said portion controlling the exhaust of fluid from the exhaust permitting passages to the outlet, and grooves around the valve chamber on the opposite outer sides of said spaced grooves, the outer groove on each side being connected to the opposite one of the spaced grooves by a passageway, said passageways being independent of each other, and said outer grooves receiving the oppositely disposed pressure faces.

4. In a fluid operated motor, the combination with a cylinder member having a piston chamber and a piston therein, of a valve chest having an open ended valve chamber, motive fluid supply means including annular grooves in the end portions of the valve chest surrounding the chamber, other annular grooves in said valve chest adjacent to the first grooves and having communication with the end portions of the piston chamber, closure plugs for the ends of the valve chest having sleeve portions that fit within the ends of the

valve chamber and extend across the grooves, 50 said tubular portions having their inner ends spaced apart and having ports communicating with the grooves, and a reciprocatory valve having its end portions operating in the sleeve portions of the plugs and controlling communication alternately between the ports of the adjacent grooves, said valve having flange portions that are of substantially the diameter of the plugs and operate between their inner ends. 60

5. In a fluid operated motor, the combination with a cylinder member having a piston chamber and a reciprocatory piston operating therein, of a valve chest having a valve chamber, means for supplying motive fluid to the end portions of the valve chest, intake passages for directing such motive fluid from the ends of the valve chest to the ends of the piston chamber, said piston chamber having exhaust permitting passages between the intake passages opening into the valve chamber between the supply means, an exhaust outlet from the valve chest between the exhaust permitting passages, a distributing valve in the valve chamber having end portions that control the passage of motive fluid from the supply means to the intake passages and spaced valve flanges that control the exhaust of fluid through the exhaust permitting passages to the outlet, the surface 80 areas of the said end portions of the valve being greater than the surface areas of said flanges, means for intermittently supplying live motive fluid alternately against said smaller surface areas of the flanges during a portion of the piston stroke, while relieving the corresponding end portion area of the valve of pressure and maintaining fluid pressure against the opposite end of the valve to prevent its movement, and means controlled by the piston as it reaches the limit of its stroke for compressing the motive fluid in the ends of the piston chamber and transmit the pressure thereof against the end portions of the valve to supplement the pressure 95 against the flanges and shift the valve.

In testimony whereof, I affix my signature.

WILLIAM G. NAISMITH.
